UNITED STATES PATENT OFFICE.

MENNE VAN VOORST, OF HERREID, SOUTH DAKOTA.

BEET-HARVESTER.

1,081,349.

Specification of Letters Patent.

Patented Dec. 16, 1913.

Application filed March 1, 1913. Serial No. 751,661.

To all whom it may concern:

Be it known that I, MENNE VAN VOORST, a citizen of the United States, residing at Herreid, in the county of Campbell and State of South Dakota, have invented certain new and useful Improvements in Beet-Harvesters, of which the following is a specification, reference being had to the accompanying drawings.

This invention relates to new and useful improvements in beet harvesters and more particularly to a device for topping and digging the beets and my object is to provide a device of this character, the general structure of which is an improvement over the numerous devices of this type, now in vogue.

A further object of the invention resides in providing a harvester consisting of a pair of frames, the one carrying the topping mechanism and the other the digging or pulling mechanism and a still further object resides in providing improved means for the operation of the various parts of the device.

Still another object of the invention resides in providing a device which is extremely simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claim.

In the accompanying drawings forming a part of this application, Figure 1 is a side elevation of the machine with a portion of the wheel nearest the observer removed. Fig. 2 is a plan view of the same. Fig. 3 is a vertical longitudinal section through the device as seen on line 3—3, Fig. 2. Fig. 4 is a transverse section as seen on line 4—4, Fig. 2; and Fig. 5 is a transverse section as seen on line 5—5, Fig. 2.

In describing my invention, I shall refer to the drawings in which similar reference characters designate corresponding parts throughout the several views and in which—

1 indicates the forward frame of the device consisting of a metal bar bent intermediate of its ends to form parallel spaced apart arms, which form the side bars of said frame, the intermediate portion of said bent bar forming the forward end of the frame. 55 Partially secured to the rear ends of the arms forming the sides of the frame 1, is the

rear frame 2, which consists of a pair of upwardly and rearwardly inclined bars 3 and a pair of substantially horizontal bars 4. These inclined and horizontal bars which form the frame 2 are secured together at their forward ends and are braced together, adjacent their rear ends by the bracing arms 5, said bars being preferably formed of angle metal. The substantially horizontal bars 4 of the frame 2, extend a short distance beyond the rear ends of the inclined bars 3 and have rotatably mounted in bearings thereon an axle 6, which, in turn, carries thereon the enlarged rear supporting wheels 7. The forward end of the front frame 1, on the other hand, is provided with a central bearing 8 in which is mounted the vertical shaft 9, the latter having a plate 10 carried at its lower end and mounted in this plate 10, is an axle 75 11 carrying the reduced front supporting wheels 12. From this construction, it will be seen that the device may be readily supported on the ground and I have provided means for retaining the rear frame in various adjusted positions with respect to the front frame. To this end, the ends of the arms of the front frame 1 are provided with the integral arcuate arms 13, the latter extending rearwardly on the sides of the rear frame 2 and provided with registering openings 14. Plates 15 which are connected to the arms 3 and 4 of the rear frame and form additional bracing means therefor, are also provided with alining openings 16 which are 80 85 adapted to register with the openings in the arcuate arms 13. A bolt or shaft 17 is disposed through the openings 16 in the plates 15 and through a pair of the registering openings 14 in the arcuate arms, and through 90 this medium, the rear frame 2 is held in a rigid position with respect to the frame 1, but is capable of adjustment with respect thereto, as is obvious from the construction described and shown.

The front frame 1 of the device may be termed a topping frame in view of the particular structure carried thereon for topping vegetables and in carrying out the idea, a vertical bearing 18 is provided on the one 105 side bar or arm of said frame, in which is rotatably and slidably mounted a shaft 19. The lower end of this shaft has a cutter 20 carried thereon, the same being provided with a plurality of arms, but which may be 110 of any desired form, and loosely connected to the upper end of this shaft 19, is one end

of a fulcrumed operating lever 21. This lever is fulcrumed intermediate of its ends on an arm 22, carried on the adjacent side bar of the frame 1 and a spring operated detent 23 carried on said lever and operated from the handle thereof, is adapted to coöperate with the ratchet 24 also mounted on the frame 1, adjacent the rear end thereof. An angular supporting arm or keeper 25 which 5 is also carried on the frame 1, on the side thereof opposed to that carrying the shaft 19, supports a rotatable horizontal shaft 26, the free end of which carries a bevel gear 27. The vertical shaft 19, above referred to, 10 also carries a bevel gear 28 of smaller dimensions than the last mentioned gear 27, the same being slidably keyed on said shaft 19 and engages said gear 27. From this construction, it will be seen that the shaft 19 15 will be rotated upon the rotation of the horizontal shaft 26 and said shaft 19 may also be raised and lowered to correspondingly raise and lower the cutting mechanism to accord with the adjustment of the 20 rear frame 2 with respect to the frame 1.

As stated, the vertical shaft 9 which carries the supporting means for the front axle 11 is slidably mounted in the bearing 8 at the forward end of the frame 1 and loosely 25 connected to the upper end of said shaft is a linking member 29, the latter being also pivotally connected to the forward end of an additional fulcrumed lever 30. The latter lever is fulcrumed intermediate of its ends 30 on an arm 31, on the angular arm or keeper 25, and a spring held detent 32 on this lever is adapted to engage the teeth of an additional ratchet 33 which is carried on the frame 1 adjacent the ratchet 24. These 35 levers 21 and 30 extend rearwardly over the frame 1 to a point adjacent the point of pivotal connection between the frames 1 and 2 and carried on a transverse bar 34 at the forward end of said frame 2, is a seat post 35 carrying the seat 36. The levers extending 40 to a point adjacent this seat 36 may be readily operated by the driver, while the machine is in use.

Mounted in bearings on the under faces of 45 the bars 3 of the frame 2 at the front and rear ends of the same, are the rollers 37 over which extends an endless conveyer 38. The rear roller 37 has a stub shaft formed at one end thereof which extends beyond the 50 side of the frame 2 and mounted on this stub shaft or the like is a gear 39 which meshes with a similar gear 40 carried on the rear axle 6. The latter gear is slidably keyed on the axle 6 and the collar carrying the 55 same is provided with a clutch face 41. A complementary clutch face 42 is formed on the inner face of one supporting wheel 7 and loosely engaged with the gear 40 is the rear 60 end of a fulcrumed operating lever 43. This 65 operating lever is fulcrumed intermediate of

its ends on a laterally extending arm 44 carried on the rear frame 2 and the handle member thereon extends forwardly to a point adjacent the seat 36, whereby the same may be readily operated by the driver. 70 From this construction, it will be seen that the rear wheel 7 may be thrown into and out of gear to cause the conveyer to be driven or stopped, as desired. Also carried on a stub shaft, projecting from the rear roller 75 on the frame 2, is a sprocket 45, over which extends an endless chain 46, said chain also extending over an additional sprocket 47, the latter being carried on one end of a transverse supporting shaft 48 which is carried 80 on the frame 2, adjacent the forward end thereof. A still further sprocket 49 is carried on this shaft over which extends an endless chain 50, said chain also extending over a sprocket 51, which is carried on the 85 outer end of the horizontal shaft 26 above referred to. Thus, it will be seen that the beet or vegetable topping mechanism will be operated simultaneously with the operation of the conveyer on the rear frame 2. 90

The forward end of the rear frame 2 which projects forward of the rear ends of the frame 1, has a shovel or digger 52 carried thereon which is adapted to engage the soil as the device is propelled to remove 95 the vegetables therefrom, and as said vegetables are removed, the same are forced through the conveyer and carried to the rear end of the frame 2. Secured to the rear ends of the inclined bars, on the frame 2, is a 100 curved channel or chute 53 into which the vegetables from the conveyer are emptied and this chute may lead to any desired device for receiving the removed vegetables.

From the foregoing description of the construction of my improved device, the operation thereof will be readily understood and it will be seen that I have provided a device which will most effectively remove the tops from vegetables growing below the 110 ground and simultaneously dig said vegetables and convey the same to a desired receptacle. It will further be seen that the device is simple and durable in construction, inexpensive to manufacture and one which will 115 be very efficient and useful in operation.

While I have particularly described the elements best adapted to perform the functions set forth, it is obvious that various changes in form, proportion and in the 120 minor details of construction may be resorted to without departing from the spirit or sacrificing any of the principles of the invention.

Having thus described this invention, 12 what I claim is:—

In a harvester of the class described, a pair of frame sections pivoted to one another in longitudinal alignment, supporting wheels carried on the forward frame section, 13

enlarged supporting wheels carried on the rear end of said rear frame section to normally dispose the latter in an inclined position with respect to the forward frame section, said rear frame section consisting of pairs of forwardly converging side bars, and connecting means between said side bars, arcuate and rearwardly extending arms formed on the rear ends of the forward frame section for disposition on the sides of said rear frame section, means in connection with said arcuate arms, and the bracing means for the

converging arms of the rear section to retain the latter in various adjusted positions with respect to the forward frame section, and ¹⁵ harvesting means carried on said frame sections.

In testimony whereof I hereunto affix my signature in the presence of two witnesses.

MENNE VAN VOORST.
